DESIGN FOR A CHAIR

Chester Hasenstein, Sheboygan, Wis.

Application November 1, 1937, Serial No. 72,564

Term of patent 3½ years

To all whom it may concern:

Be it known that I, Chester Hasenstein, a citizen of the United States, residing at Sheboygan, in the county of Sheboygan and State of Wisconsin, have invented a new, original, and ornamental Design for a Chair, of which the following is a specification, reference being had to the accompanying drawing, forming part thereof.

In the drawing:

Figure 1 is a side view of a chair and Figure 2, a front view thereof, showing my new design.

I claim:

The ornamental design for a chair, as shown.

CHESTER HASENSTEIN.
